UNITED STATES PATENT OFFICE.

WILLIAM E. GADDIS, OF McCUNE, KANSAS, ASSIGNOR OF ONE-THIRD TO HANCLE L. STEWART, OF McCUNE, KANSAS.

ROAD LEVELER.

Application filed July 23, 1921. Serial No. 487,065.

To all whom it may concern:

Be it known that I, WILLIAM E. GADDIS, a citizen of the United States, residing at McCune, in the county of Crawford and State of Kansas, have invented new and useful Improvements in Road Levelers, of which the following is a specification.

This invention relates to road scrapers, and has for its object the provision of an improved device for scraping and leveling roads, the device being so constructed that the depth of cut may be quickly and easily regulated, separate cutting blades being provided and the adjustment being such that one blade may be caused to cut deeper than the other, the adjusting means involving the provision of a plurality of supporting wheels, either pair of which may be independently moved, the blades being carried rigidly by the supporting frame.

An important object is the provision of a device of this character which is provided with an angularly adjustable auxiliary laterally extending blade which is for the purpose of scraping a ditch alongside the road, the dirt scraped up by this auxiliary scraper being thrown in the path of travel of the main scraper blades.

Another object is the provision of a device of this character in which the arrangement is such that inequalities in the road will be eliminated, the high spots being cut down and the low spots being filled so that a perfectly level surface will be produced.

An additional object is the provision of a device of this character which will be simple and inexpensive in manufacture, easy to adjust, highly efficient in use, durable in service, and a general improvement in the art.

With the above and other objects and advantages in view, the invention consists in the details of construction to be hereinafter more fully described and claimed and illustrated in the accompanying drawings in which—

Figure 1 is a plan view of my device,

Figure 2 is a side elevation thereof,

Figure 3 is a rear end view,

Figure 4 is a front end view,

Figure 5 is an enlarged detail view show-

ing the construction and mounting of the auxiliary blade,

Figure 6 is a detail sectional view on the line 6—6 of Figure 1,

Figure 7 is a detail sectional view on the line 7—7 of Figure 1,

Figure 8 is a section on the line 8—8 of Figure 1, and Figure 9 is a section on the line 9—9 of Figure 1,

Figure 10 is a detail sectional view on the line 10—10 of Figure 1 showing the ball and socket mounting,

Figure 11 is a similar view on the line 11—11 of Figure 1 and

Figure 12 is a detail prospective view of the control lever.

Referring more particularly to the drawings, I have shown my device as comprising a rectangular supporting frame formed preferably of channel iron and including side bars 10, a front end bar 11, and a rear end bar 12. The bars 11 and 12 are much narrower than the bars 10 so as not to strike against any obstructions in the roadway, it being understood that the upper edges of the bars 10, 11 and 12 are all flush. These side bars 10 are formed with upwardly extending arches 13 and 14 located, as shown, and the purpose of which will be hereinafter made apparent. It is preferable to provide suitable corner castings 15 at all the corners of the frame for the purpose of making a strong and rigid structure. While channel iron is mentioned as being the proper material, it is to be understood that I do not desire to limit myself in this regard as I might find it convenient or expedient to use I beams or other bars. Extending transversely across the center of the rectangular frame is a bar 16 and located to the rear of this bar is a platform 17 upon which is mounted a seat 18 for the operator. Located adjacent this seat and carried by the platform 17 is a control mechanism to be described.

Extending diagonally across the frame in advance of the bar 16, is a mold board 19 which has its ends provided with ball members 20 engaged within sockets 21 formed on the confronting faces of the side bars 10. The lower edge of this mold board consti-

tutes the forward scraper blade 22. Extending across the rear portion of the frame is an oppositely inclined mold board 23 having its ends provided with ball members 24 engaged within sockets 25 on the confronting faces of the side bars. The rearmost end of this mold board is located adjacent the arch 13. The lower edge of this mold board constitutes the rear cutting blade 26. The numeral 27 designates brace rods which are connected with the bar 16 and with the mold board 19, and the numeral 28 designates similar brace bars connected with the bar 16 and the rear mold board 23. It should be stated that the numeral 29 designates inclined brace bars which are connected with the bar 16 and with the side bar 10 whereby to reinforce the structure.

Located at the rear portion of the frame 20 is a movable frame 30 formed of a truss rod structure of archlike formation and within which are journaled ground engaging wheels 31. The extremities of the frame 30 are provided with lateral extensions 32 constituting 25 trunnions which are rotatable within bearings 33 secured to the bar 10. Secured to the uppermost member of the frame 30 are forwardly converging rods 34 which are connected with a link 35 which is pivotally connected with a control lever 36 pivoted upon the platform 17 and provided with a grip release latch 37 cooperating with a notched segment 38 whereby to hold the lever 36 in adjusted position. By adjusting the lever 35 36 backward or forward it will be apparent that the frame 30 may be swung upon its trunnions 32 and this will result in raising or lowering the rear end of the main frame for varying the depth of penetration of the rear blade 26.

Extending diagonally at the forward corners of the main frame are bars 39 upon which are pivotally mounted the depending arms 40 of a frame which includes a horizontal bar 41 and swivelly mounted upon the lower ends of these arms 40 are yokes 42 within which are journaled wheels 43. By this construction it will be seen that the wheels 43 are free to turn in any direction 45 in the same manner as a caster. Connected with the rod 41 is a rearwardly extending reach rod 44 which is pivotally connected with a lever 45 pivoted upon the platform 17 and having a grip released latch 46 cooperating with a notched segment 47. By this construction it will be seen that by moving the lever 45 the frame, including the arms 40, may be rocked upon the pivots 40 and in this way the forward end of the main frame may be moved up or down with respect to the ground so as to vary the depth 50 of penetration of the forward cutting blade 22.

Hinged upon one side bar 10 adjacent the 55 arch 14, as shown at 48, is a mold board

49 which has its lower edge constituting an auxiliary scraper blade 50. Connected with the free end of this mold board 49 is a chain or other flexible member 51 which is connected with the tongue 52 or other draft device which is secured centrally to the front bar 11. Also connected with the free end of this mold board 49 is a rod 52 which has its rear end pivotally connected with a lever 53 having a grip released latch 54 cooperating with a notched segment 55.

In the operation of the device it will be seen that when it is drawn along the ground by animals or a tractor, the blades 22 and 26 will scrape the ground to a greater or less depth, depending upon the adjustment of the rear frame 30 and the forward frame 41, as will be readily apparent, the high spots being of course cut down and the dirt removed therefrom being scraped into the low spots so that a level surface will be left after the device has passed over. By adjusting the lever 53 so as to press and hold the mold board 49 and blade 50 in a downwardly inclined position, it will be apparent that a ditch alongside the road may be scraped, the dirt dragged loose by the blade 50 passing through the arch 14 in the path of travel of the blade 22 and this additional dirt will of course be distributed along the roadway.

From the foregoing description and a study of the drawings it will be apparent that I have thus provided a simply constructed and consequently inexpensive road scraping and leveling device which will be unusually efficient in operation and which will not only operate to level a road but which will also scrape or clear a ditch at the same time. Owing to the considerable length of the device it is apparent that irregularities in the road will be eliminated as the device will very efficiently cut down the high spots and scrape this surplus dirt into the hollows. It will be observed that the control mechanism is very simple and involves the adjustment of the frame with respect to the ground, the main blades being entirely stationary with respect to the frame.

While I have shown and described the preferred embodiment of my invention, it is of course to be understood that I reserve the right to make such changes in the form, construction and arrangement of parts as will not depart from the spirit of the invention or the scope of the subjoined claims.

Having thus described my invention I claim:

1. A device of the character described comprising an elongated rectangular frame, a draft tongue connected therewith, transverse scraper blades mounted therein, an auxiliary mold board and blade pivotally mounted at one side of the main frame and extending laterally therefrom, a flexible member connected with the free end of

said auxiliary mold board and with said draft tongue, a rod pivotally connected with the free end of said mold board, and a lever pivotally connected with said rod and movable over a notched segment whereby to hold said auxiliary mold board in a downwardly inclined direction for scraping a ditch beside a roadway.

2. A device of the character described comprising a rectangular frame, scraper members mounted therein, draft means connected with said frame, and an auxiliary

scraper mechanism including a mold board pivoted at one side of said frame, a flexible member connected with said mold board for 15 limiting outward swinging movement thereof, a notched segment stationarily mounted upon the frame, a lever having a grip released locking pawl co-operating with said segment and a link connected with said lever 20 and with said mold board.

In testimony whereof I affix my signature.

WILLIAM E. GADDIS.
